Filed Mar. 20, 1964, Ser. No. 79,140

Term of patent 3½ years

(Cl. D34—15)

FIG. 1

FIG. 2

FIG. 3

FIG. 1 is a view in perspective of a toy ball gyrator of my design.

FIG. 2 is a fragmentary view in side elevation of the handle portion of the gyrator, and

FIG. 3 is an end elevation of the handle.

The broken lines indicating a ball in FIG. 1 are for illustrative purposes only.

The characteristic feature of my design resides in the particular configuration of the handle portion as shown.

I claim:

The ornamental design for a toy ball gyrator or similar article, as shown and described.
